(No Model.)

G. A. RICHARDS.
VEHICLE SPRING.

No. 427,189.

Patented May 6, 1890.

UNITED STATES PATENT OFFICE.

GEORGE A. RICHARDS, OF NEW LONDON, CONNECTICUT.

VEHICLE-SPRING.

SPECIFICATION forming part of Letters Patent No. 427,189, dated May 6, 1890.

Application filed February 25, 1890. Serial No. 341,679. (No model.)

To all whom it may concern:

Be it known that I, GEORGE A. RICHARDS, a citizen of New London, in the county of New London and State of Connecticut, have 5 invented certain new and useful Improvements in Vehicle-Springs; and I do hereby declare the following to be a full, clear, and exact description of the invention, such as will enable others skilled in the art to which 10 it appertains to make and use the same.

My invention relates to an improvement in vehicle-springs, the object being to produce a vehicle-spring which shall be simple in construction and effective in the performance of 15 its functions.

A further object is to so construct a vehicle-spring that it shall be self-adjusting and its carrying capacity shall exceed that of a semi-elliptical spring, whereby it will accommodate 20 itself equally to one or more riders.

A further object is to so construct the spring that it will work compactly, will not spread the body of the vehicle nor wear into the same, and so that it will not twist the sills of the 25 vehicle nor strain the bolts.

A further object is to produce a vehicle-spring which will be practically noiseless in its operation.

A further object is to produce a spring-30 cushion made of a single piece of metal, and to so construct and arrange the same that a large cushion may be employed.

With these objects in view the invention 35 consists in certain novel features of construction and combinations and arrangements of parts, as hereinafter set forth, and pointed out in the claims.

In the accompanying drawings, Figure 1 represents an elevation, partly in section, of 40 my invention. Fig. 2 is a view of a modification.

A represents the bottom board of a vehicle, preferably having a recess *a* in its under face at or near each end, B B the side-boards of 45 the vehicle, and C C the sills of the vehicle-body.

Located beneath the vehicle-body at each end thereof is a metal spring-bar D, which is secured to the under face of the bottom board 50 A by means of suitable bolts *b* at or beyond opposite ends of the recess *a* and to the sills

C by means of suitable bolts *c*. The spring-bar D extends from one side-board B of the vehicle to the other, and at its ends said spring-bar is bent upon itself and extended 55 inwardly toward the center of the spring-bar in the form of loops to produce spring-cushions F. The cushions F are so bent as to nearly meet at the center of the spring-bar E. A spring G is secured at its center to the 60 spring-bar D and cushions F by means of bolts *e f* or other means, said bolts passing through the spring-bar, the spring, and the ends of the cushions F, thus binding these parts together at a point in line with the longitudinal axis of the vehicle. By making the 65 recess *a* in the under face of the bottom board of the vehicle it will be seen that a springing or vibrating action is permitted to the spring-bar D.

With the combination of united spring bar and cushion, as above described, attached to a spring, the vehicle-body can be hung low, and it will retain its easy-riding qualities irrespective of the weight carried. The above 75 combination will not spread the body of the vehicle or wear into the same; will not twist the sills nor strain the bolts; is absolutely noiseless; gives one-third longer cushion than any other in use, so far as I am aware, (for 80 same width of body,) which prevents bending or breaking of springs, and will not allow it to strike the reach. It will prevent the rolling motion of the vehicle (which is a very valuable consideration) and still retain the center 85 vibration, giving to the spring perfect freedom of action in all its parts and decreasing its liability to break. It also saves a spring-bar to the carriage-builder in making a carriage, as one is not needed, while the cost of applying 90 this invention will be but little (if any) greater than that of other cushion-springs now in use.

My improvement is also applicable for use upon car-springs, in which case two spring 95 bars and cushions will preferably be employed, each secured to springs, as shown in Fig. 2, or by other means or in other ways, as necessity may require. In fact, the invention is applicable for use upon any style of conveyance using springs, irrespective of its 100 weight or size.

Having fully described my invention, what I claim as new, and desire to secure by Letters Patent, is—

1. The combination of a spring bar and cushion formed of a single piece of metal, the ends of the cushion being bent around and secured to the spring-bar at or near its center, substantially as set forth.
2. The combination of a spring bar and cushion formed of a single piece of metal, the ends of the piece being bent around and secured to the spring-bar at or near its center, and a separate spring secured to the spring bar and cushion, substantially as set forth.
3. The combination of a spring bar and cushion made of a single piece of metal and bent to produce loops at opposite sides of its center, and a spring secured at its center to the spring bar and cushion by the same bolts or devices which hold the ends of the cushion to the spring-bar, substantially as set forth.
4. The combination of a spring-bar bent to produce loops or cushions, the free ends of said cushions being secured to the spring-bar

at or near its center, substantially as set forth.

5. The combination of a spring-bar bent to produce loops or cushions, the ends of said cushions being so bent as to meet or nearly meet at the center of the spring-bar, a spring, and bolts passing through the spring-bar, cushions, and spring and securing these parts together at a point in line with the longitudinal axis of the vehicle, substantially as set forth.

6. The combination, with a vehicle-body having a recess in its bottom, of a spring-bar secured to the bottom of the vehicle and extending across said recess, said spring-bar being bent to produce spring-cushions, and a spring secured to the spring bar and cushions, substantially as set forth.

In testimony whereof I have signed this specification in the presence of two subscribing witnesses.

GEO. A. RICHARDS.
